CARL P. STUART, OF GORHAM, NEW HAMPSHIRE.

MAGAZINE ATTACHMENT FOR FIREARMS.

1,244,794.

Specification of Letters Patent. Patented Oct. 30, 1917.

Application filed June 13, 1917. Serial No. 174,582.

To all whom it may concern:

Be it known that I, CARL P. STUART, a citizen of the United States, residing at Gorham, in the county of Coos and State of New Hampshire, have invented certain new and useful Improvements in Magazine Attachments for Firearms, of which the following is a specification.

This invention relates to firearms, and more particularly to an improved cartridge magazine for attachment to a gun or rifle.

The primary object of the invention is to provide an improved cartridge magazine designed to contain a supply of cartridges so associated with the gun as to permit the cartridges to be fed into firing position as the gun is being used, while the empty shells will be retained within the magazine.

The invention also aims to provide a magazine of this character associated with the mechanism adapted to move the cartridges into and out of the firing chamber so that the shells may be replaced in the magazine during the operation of the breech bolt.

A further object of this invention is the provision of a magazine attachment for firearms which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which:

Figure 1 is a side elevation of the cartridge magazine constructed in accordance with my invention.

Fig. 2 is an end elevation of the same.

Fig. 3 is a section on the line 3—3 of Fig. 1.

Fig. 4 is a top view of the magazine.

Fig. 5 is a section on the line 5—5 of Fig. 1.

Fig. 6 is a section on the line 6—6 of Fig. 2.

Fig. 7 is a detail fragmentary elevation of the magazine.

Fig. 8 is a fragmentary longitudinal section of the breech of a gun showing the invention applied thereto.

Fig. 9 is a detailed section through the breach.

Fig. 10 is a detail section of a fragment of the invention.

Fig. 11 is a section on the line 11—11 of Fig. 8.

Fig. 12 is a section on the line 12—12 of Fig. 8.

Referring to these drawings, wherein is illustrated the preferred form of my invention, and in which like numerals of reference indicate corresponding parts through the several views, the breech mechanism and construction of the gun may be of any preferred type and it is my intention to provide the attachment so that it may be applied to guns and rifles of the most modern type, making only the necessary alterations to permit application of the invention.

As shown particularly in Figs. 1 to 7 of the drawing, the cartridge magazine comprises a receptacle 1 which is of a length slightly greater than the length of the ordinary cartridge. The upper and lower walls 2 and 3 are of semi-cylindrical formation and the side walls are sufficiently spaced apart to permit two rows of cartridges to be received within the container and to provide for a dividing partition 4. This partition 4 extends lengthwise of the container in the exact center thereof and is preferably constructed from light wood or other suitable light material. The upper and lower edges of the partition are spaced away from the upper and lower curved walls 2 and 3 so that a continuous passage way is provided within the container around the partition 4 as shown to advantage in Fig. 3 of the drawing. Within this passage way a number of cartridges are placed and so disposed as to permit one cartridge to be directly above the upper edge of the partition 4 for a purpose presently described.

Fixed to each end wall of the container is a spring casing 6 which consists of a length of channel iron suitably secured to the end of the container or magazine and having its upper end open for the reception of a sliding clip 7. Within each spring casing is a coil expansion spring 8 which bears against the clip 7 and urges the same outwardly of the casing and the outer end of each clip is provided with a finger 9.

The top curved wall 2 of the magazine is provided with a longitudinal slot 10 and one side wall is divided into leaves 11 and 12 which are hinged together as at 13 for permitting the side of the magazine to be opened for placing a number of cartridges within the magazine. The upper end of each end wall is provided with an opening 14 sufficient to permit movement of one of the cartridges inwardly or outwardly of the magazine, but these openings are normally closed by the clips 7 when the magazine is not mounted upon the rifle or gun so that the uppermost cartridge will be retained in place within the magazine.

Referring now particularly to Figs. 8 to 11 it will be noted that the magazine is mounted directly beneath the breech mechanism of the rifle and slightly rearwardly of the firing chamber A. A retaining frame 15 consists of an arm 16 attached beneath the firing chamber A and depending therefrom and to which is pivoted a supporting arm 17 extending rearwardly beneath the bottom of the magazine and releasably held to the trigger guard B by a latch 18. Interposed between the support 17 and the bottom of the magazine is a flat spring 19 tending to urge the magazine upwardly into tight engagement with the adjacent portion of the breech. As shown to advantage in Fig. 8 of the drawing, when the magazine is mounted in position, the clip fingers 9 are depressed against the action of the springs 8, one finger being received in a convenient recess in the arm 16 while the other clip is engaged by a projection 20 fixedly arranged beneath the sliding breech bolt C. The magazine is so mounted, with respect to the breech bolt C, that the latter may slide longitudinally through the space in the magazine normally occupied by the uppermost cartridge so that the ends of the breech bolt will project through the openings in the end walls of the magazine. The breech bolt C will be reciprocated in the usual manner by the usual lever disposed at the exterior of the rifle and within convenient reach of the user.

Pivoted on a pivot pin 21 is a loading lever 22 which has a cartridge engaging finger 23 extending through a slot 24 formed in one of the side walls of the magazine. As shown in detail in Fig. 12 this finger 23 has a lip 25 curved to fit the curve of one of the cartridges and this lip will operate to thrust one of the cartridges upwardly when the lever is operated. The actuation of the lever is accomplished through the medium of the cam 26 which includes the beveled edge 27 formed on the rearwardly extending portion of the lever. This cam or beveled edge will be engaged with the rear end of the breech bolt C when the latter is moved rearwardly during the reciprocation of the bolt by the user and

this engagement of the breech bolt with the beveled edge will swing the lever and cause the lip 25 to thrust a cartridge upwardly into the space evacuated by the forward end of the breech bolt.

In order that the empty shell may be withdrawn from the firing chamber A by the breech bolt when the latter is moved rearwardly, I have provided an extracting lever 28 pivotally mounted in a longitudinal recess in the top of the breech bolt. The forward end of this lever 28 has a hook 29 which engages the usual bead on the end of the cartridge shell so that the latter will be withdrawn when the bolt is moved rearwardly. The rear end 30 of the extracting lever 28 is disposed over a depressed portion 31 of the recess in the breech bolt and this portion of the lever carries a lug 32 projecting into a longitudinal groove 33 formed in the upper portion of the gun frame. The rear end of this groove is beveled so that when the breech bolt is pulled rearwardly the lug will be forced downwardly and the end of the lever pressed into the depression 31 thus causing the hook 29 to be released from the end of the cartridge shell whereupon the pressure of the cartridge forced upwardly by the loading lever 22 will cause the shell to be pressed downwardly on the opposite side of the magazine. It will be apparent, therefore, that each actuation of the breech bolt will cause the removal of the empty cartridge from the firing chamber; the insertion of a fresh cartridge in position in alignment with the breech bolt; and the retention of the empty shell in the space provided by the movement of the fresh cartridge.

In order that the fresh cartridge may be held out of the firing chamber while the gun is not in use and to prevent the cartridge from sliding downwardly into the chamber when the muzzle of the gun is held downwardly, I have provided a safety catch, shown in detail in Figs. 9 and 10 of the drawing, and which includes a latch 34 pivotally mounted in a recess 35 provided in a convenient portion of the gun frame. This lever includes a plate 36 formed on its end and adapted to swing into position over the end of the magazine as shown by full lines in Fig. 9. The free edge of this plate is bent and curved to form a guard 37 engageable with the point of the bullet forming a part of the cartridge so that the bullet will be prevented from sliding downwardly when the muzzle of the gun is pointed downwardly. The curve of the guard 37, however, permits the latch to be swung into the recess 35 when pressure is applied to the breech bolt for forcing the cartridge into the firing chamber. The latch swings into the recess against the pressure exerted by a flat spring 38 and the latter

will act to force the latch again into operative position whenever the mechanism is actuated to remove the empty shell.

The operation of the mechanism will be readily apparent and it is to be pointed out that the magazine may be constructed to contain a large quantity of cartridges; that is, the length of the cartridge magazine may be increased so that it may depend considerably below the gun. The empty flying shells, which is one of the objectionable features of the modern firearm, is eliminated by the device and it will be obvious that it may be employed equally as well on machine guns as on rifles and small firearms.

From the foregoing it will be observed that a very simple and durable magazine attachment for firearms has been provided, the details of which embody the preferred form. I desire it to be understood, however, that slight changes in the minor details of construction may be made without departing from the spirit of the invention or the scope of the claims hereunto appended.

I claim as my invention:

1. In a device of the character described, the combination with a breech mechanism including a sliding breech bolt, of a cartridge magazine having a plurality of cartridges arranged therein and mounted to permit the said breech bolt to slide through the magazine to force one of the cartridges out of the said chamber, means mounted upon the sliding bolt to retain a hold on the cartridge to withdraw the same into the magazine, and a loading lever engageable by the said breech bolt and adapted to swing for forcing one of the cartridges into the space evacuated by the said bolt.

2. In a device of the character described, the combination with a breech mechanism including a breech bolt and a firing chamber, of a cartridge magazine secured in position to permit the breech bolt to slide therethrough when the said breech bolt is reciprocated, means carried by the breech bolt to engage the empty cartridge for withdrawing the same from the firing chamber into the said magazine, and means adapted to be actuated by the rearward sliding movement of the breech bolt for forcing a fresh cartridge into position in the space evacuated by the breech bolt and causing the said fresh cartridge to force the said empty cartridge from the firing chamber downwardly in the said magazine.

3. In a device of the character described, the combination with a breech mechanism including a breech bolt and a firing chamber, of a cartridge magazine containing a plurality of cartridges and mounted to permit the uppermost cartridge to be placed in alinement with the said bolt whereby the latter may force the cartridge into the said firing chamber and out of the said mag-

azine, means carried by the bolt to withdraw the empty cartridge from the firing chamber and into the said magazine, and a loading lever engaged by the said bolt and adapted to be actuated for forcing a fresh cartridge into the space occupied by the said empty shell after the latter is drawn into the magazine by the said bolt.

4. In a device of the character described, the combination with a breech mechanism including a breech bolt and a firing chamber, of a cartridge magazine mounted in position to permit the breech bolt to slide through the magazine, the said magazine being provided with means to form a passage way through which cartridges may be moved, an extracting lever carried by the bolt and adapted to retain a hold on the cartridge forced from the magazine by the bolt so that the discharged cartridge in the firing chamber may be withdrawn therefrom into the said magazine, and means adapted to be actuated by the said sliding bolt and extending into the magazine to engage a fresh cartridge to force the latter into alinement with the said bolt and to force the empty cartridge downwardly into the said magazine.

5. In a device of the character described, the combination with a breech mechanism including a breech bolt and a firing chamber, of a cartridge magazine mounted in position to permit the breech bolt to slide through the magazine, the said magazine being provided with means to form a passage way through which cartridges may be moved, an extracting lever carried by the bolt and adapted to retain a hold on the cartridge forced from the magazine by the bolt so that the discharged cartridge in the firing chamber may be withdrawn therefrom into the said magazine, and means adapted to be actuated by the said sliding bolt and extending into the magazine to engage a fresh cartridge to force the latter into alinement with the said bolt and to force the empty cartridge downwardly into the said magazine, the said means including a curved lip adapted to fit the curve of the cartridge, the said magazine having a convenient opening to permit the said lip to extend into the magazine to engage the cartridge.

6. In a device of the character described, the combination with a breech mechanism including a sliding breech bolt and a firing chamber, of a cartridge magazine mounted to permit the sliding bolt to pass therethrough to force a cartridge into the said chamber, means carried by the bolt to extract the empty cartridge from the chamber, a loading lever pivotally mounted and adapted to be actuated by the said sliding bolt to force the empty cartridge out of alinement with the bolt and to move a fresh

cartridge into alinement with the same, a guard means disposed at the opening in the firing chamber to maintain the fresh cartridge in the magazine until said bolt is actuated to force the cartridge into the firing chamber.

7. In a device of the character described, the combination with a breech mechanism including a sliding breech bolt and a firing chamber, of a cartridge magazine mounted to permit the sliding bolt to pass therethrough to force a cartridge into the said chamber, means carried by the bolt to extract the empty cartridge from the chamber, a loading lever pivotally mounted and adapted to be actuated by the said sliding bolt to force the empty cartridge out of

alinement with the bolt and to move a fresh cartridge into alinement with the same, a guard member pivotally mounted and including a spring pressed plate adapted to be held in alinement with the bolt, and means formed on the plate and adapted to engage the proximate end of the fresh cartridge whereby the guard member will be forced out of alinement with the bolt when the cartridge is forced into the firing chamber. 20 25

In testimony whereof I affix my signature in presence of two witnesses.

CARL P. STUART.
